UNITED STATES PATENT OFFICE.

FREDERICK C. YATES, OF WATERBURY, CONNECTICUT.

PUNCHING TOOL.

Application filed June 27, 1922. Serial No. 571,228.

To all whom it may concern:

Be it known that I, FREDERICK C. YATES, a citizen of Canada, and a resident of Waterbury, county of New Haven, and State of Connecticut, have invented certain new and useful Improvements in Punching Tools, of which the following is a specification.

This invention relates to punching tools, and more particularly to a center-punch or 10 prick-punch for making indentations upon a metal surface.

One object of the invention is to provide a punch of this nature, by means of which indentations of uniform depth may be obtained.

A further object is to provide a simple form of punch having only a few parts, which will not easily get out of order, and which will be simple, and cheap to manufacture.

A further object is to provide a punching tool of the above nature which will be highly efficient and durable in use.

With these and other objects in view, there 25 has been illustrated on the accompanying drawing several forms in which the invention may be conveniently embodied in practice.

Fig. 1 represents a side view of the assembled punching tool, showing in perspective, a block of metal with which the tool is to be employed.

Fig. 2 is a side sectional view of the same.

Fig. 3 is a top view of the retaining spring 35 shown in detached position.

Fig. 4 is a side view of a modified form of tool insert, adapted to be used for upsetting the heads of rivets.

Fig. 5 is a side view of another modified 40 form of tool insert having flat ends which are adapted to be used as nail sets.

Fig. 6 is a perspective view of a still further modified form of tool insert, having cup-shaped ends for resiliently holding pivot 45 pins or the like preparatory to forcing them into position in clock-work or other mechanism.

In marking metal surfaces in the past, it has been customary for the mechanic to 50 hold a small punching tool in one hand and to strike the tool a series of blows with a hammer carried in the other hand. In practice, when using this method to produce a series of marks, it was found that the indentations were not uniform, but of various sizes. Attempts have been made to manu-

facture an instrument which would produce uniform indentations, and many automatic punching tools have been devised for this purpose. These automatic punching tools, 60 however, were necessarily of complicated and delicate constructions, and were also quite troublesome and expensive to manufacture.

By means of the present invention, a 65 punching tool has been provided which is cheap to manufacture and which will enable a mechanic to produce uniform indentations upon the surface of a metal. This tool which may be readily operated with 70 one hand, contains no complicated or delicate mechanism, but on the contrary is of simple, strong, rigid, and durable construction, and practically fool-proof.

Referring now to the drawings in which 75 like reference numerals denote corresponding parts throughout the several views, the numeral 10 represents a hollow tubular barrel provided with a head 11, a pointed tool insert 12, and a hammer member 13 slid- 80 able on said barrel. The inner surface of the barrel 10 is threaded at 15 to receive the lower end of the head 11, and the bottom of the inner surface 14 of the barrel is prefer- 85 ably slightly tapered at 16 to snugly fit about tapered neck sections 17, 17 of the tool insert 12. If desired, the inner surface 16 may be threaded instead of tapered, in which case, the neck sections of the tool insert 12 would also be threaded. The barrel 10 may be made solid and have the striking 90 flange and tool member formed integral therewith within the scope of the invention.

The head 11 is provided with a hollow center 18 having its upper end 19 countersunk 95 in the form of a "bell-mouth" to afford a thumb-hold for the hand of the user. The outer surface of the head is provided with an enlarged cylindrical finger gripping section 20, preferably knurled, below which is 100 an intermediate smooth cylindrical section 21, terminating in a shoulder 22. Immediately below the shoulder 22 is a short smooth section 23 of reduced diameter, and a threaded section 24 adapted to engage the 105 threads 15 on the inside of the barrel.

As clearly shown in Fig. 2, an annular groove 23^a is provided between the shoulder 22 and the barrel 10. This groove 23^a is provided with a base 23, its sides being 110 formed by the shoulder 22 of the head and the upper end 25 of the barrel. A circular

ring or spring 26, preferably formed of resilient steel wire, is seated in the groove and normally has its ends spaced apart as shown in Fig. 3, but when compressed the ends of 5 the spring 26 will be adjacent one another.

The sliding hammer 13 is provided with a pair of interior annular grooves 27, 27^a of substantially semicircular cross section, within which the spring 26 is adapted to 10 engage in its normal expanded condition, and hold the hammer at the top of the barrel 10. The middle portion 28 of the hollow bore of the hammer is adapted to slidably fit over the barrel 10, as shown in 15 Fig. 2. The ends of the hollow bore of the hammer are enlarged in diameter and flared outwardly at 29, 29^a, to a larger diameter than the ring 26 in its expanded condition. By means of this construction, the hammer 20 may be readily forced upwardly and the spring compressed, into their initial relative locked positions.

The edges between the hammer grooves 27 and 27^a and the enlarged flared portions 29 and 29^a are chamfered—the chamfer between the groove 27 and the flared portion 29 being steeper than that between the groove 27^a and the flared portion 29^a. It will thus be seen that the hammer will be 30 more easily released, and will strike a weaker blow in the first instance—that shown in Fig. 2—than in the second instance—the reverse position.

The exterior of the hammer 13 is substantially cylindrical, and is provided with end flanges 30, preferably knurled. The middle section 31 of the exterior of the hammer is smooth, and is connected to the end flanges 30 by conical portions 32.

10 The tool insert or work-engaging member 12, as shown in Figs. 1 and 2, is provided with a central anvil or flange 32^a of enlarged diameter, adjoining the pair of tapered sections 17, previously mentioned. Beyond the 15 tapered sections 17, the tool insert is also provided with a pair of smooth sections 33 having a greater taper than the sections 17, and terminating in conical points 34, 35. The points 34, 35 are preferably of different 20 sizes in order to permit indentations of different shapes to be produced. In practice, each tool will be provided with a plurality of double-ended tool inserts, so that any desired range of sizes may be obtained.

25 In operation, assuming the hammer 13 to be resting on the anvil 32^a, the hammer will be moved up along the barrel 10 as far as possible, to its initial position. In this initial position, the split ring 26 will be seated 30 in the annular groove 27 on the inside of the hammer, and will also extend part way into the groove 27^a. The hammer 13 will thus be held from dropping down the barrel 10.

35 When it is desired to use the punch, the

operator will grasp the instrument and will push downwardly on the hammer until the pressure on the ring 26 will cause it to contract into the groove 27^a until it has completely left the groove 27. The hammer 13 70 will then be released, and under the continued force applied thereto will slide down the barrel 10, striking the flange or anvil 32^a and causing the punch point 35 to make an indentation in the surface of the metal block 36.

75 By means of the present invention, the danger of slippage of the tool along the surface of the metal is reduced to the minimum due to the fact that the punch point 80 is always held against the metal surface with a strong pressure.

85 While the tool insert herein illustrated is adapted for use in prick-punching the surface of a metal, other forms of tool inserts may be employed within the scope of the present invention. Thus the ends of the tool insert may be provided with engraving implements, or with chisels for cutting the 90 surface of the metal, stone, or other material being operated upon.

95 Another important use for the present invention is for upsetting the ends of rivets or for inserting pivot pins into watches or other mechanisms. In these two cases, the 100 tool inserts employed will have concave and cup-shaped ends respectively.

105 In addition, if desired, tool inserts having flat ends serving as nail sets, may be employed. With such nail sets, it may be 110 found desirable to magnetize the tool insert so as to cause the nails to adhere to the tool.

115 Figs. 4, 5, and 6 illustrate several modified forms of tool inserts which may be employed in the punching tool. Fig. 4 represents a tool insert having a pair of rivet sets 35, 35^a upon its extremities. The rivet sets 35, 35^a are concaved or dished in the form 120 to be given to the rivet head. The dished end 35 is preferably flatter and of larger diameter than the end 35^a, so that if desired, the former may be used to start the heading of the rivet, and the latter to finish it. Threaded cylindrical sections 36^a, 36^a, are 125 provided adjacent the anvil 32^a, and are adapted to be screwed into corresponding threads formed in the barrel 10.

130 Fig. 5 discloses a tool insert having nail sets 37, 38 upon its ends. The ends of the nail sets are flat and preferably of different size so that nails, brads or tacks of different dimensions may be operated on. The tool insert in this instance may be made of magnetized iron so that the iron fastenings will 135 be held against the flat ends of the nail sets 37, 38, when the tool is lifted, and even when in an inclined or vertical position.

140 In Fig. 6, a tool insert is disclosed having its ends formed in the shape of cups 39, 40.

Each of the cups 39, 40, is split into three resilient prongs 41, as clearly shown on the drawing. These prongs are adapted to resiliently grip various sizes of rivets, pinions, pintles, etc., preparatory to driving them into place in clock-work or other mechanisms.

In case it is desired to reduce or increase the force of the impact, it will only be necessary to change the size or material of the spring wire 26. Another method of varying the impact force is to employ hammers or barrels of different lengths or weights. Still another method of varying the force of the impact is to change the angle of the chamber between the groove 27 and the flared section 29, or to change the diameter of said flared section 29.

It will thus be seen that by means of this invention, a simple form of punching tool has been provided which may be operated with one hand if desired, and will produce indentations, fully as uniform as more expensive types of complicated automatic punches. Yet at the same time, the present punching tool has the advantage of being constructed of relatively few parts which cannot get out of order, all of the parts being easily accessible for cleaning.

While there have been disclosed in this specification, one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an instrument for producing prick marks on the surface of a metal, a body having a punch point at the lower end thereof, a tubular hammer slidable on the outside of said body for engaging the lower end of said body and causing the punch point to mark the metal, and means for releasably holding said hammer at the top of said body.

2. In a metal-punching tool, a tubular barrel, a pointed punch secured in one end of said barrel, a tubular hammer slidable on the outside of said barrel and adapted to engage said pointed punch, and means for initially holding said hammer near the top of said tubular barrel yet permitting its sudden release upon the application of a predetermined pressure upon said hammer.

3. In a metal-punching tool, a body, a detachable double-pointed tool insert secured to the lower end of said body, said tool insert having a flange below said body, a tubular hammer slidable on the outside of said

body, and adapted to engage said flange for delivering an impact to the tool insert, and means for initially holding the hammer near the top of said body, said means being released upon the application of a predetermined downward pressure upon said hammer.

4. In a punching tool, a barrel, a head threaded into the upper end of said barrel, a shoulder on said head spaced from the end of said barrel to form a groove, a resilient ring seated in said groove, a hammer member mounted on said barrel, a tool insert, said barrel having its bottom inner surface outwardly tapered, said tool insert having a tapered portion adapted to fit in the tapered section of said barrel, said resilient ring adapted to be compressed into said groove by the downward movement of said hammer, whereby said hammer will be released and permitted to strike a blow upon said tool insert.

5. In a punching tool, a shaft having a punching point upon one end, a hammer, said shaft and hammer having alined annular grooves, a spring fitting jointly within said grooves, said spring being adapted to be compressed into the shaft-groove by the downward movement of said hammer to release said hammer, and a stop carried by said shaft for suddenly checking the downward movement of said hammer, whereby a sharp impact will be given to the punching point.

6. In a punching tool, a shaft having a punching point at its bottom end, a groove on said shaft near its top end, a spring seated in said groove, and a hammer slideable on said shaft, said hammer having a pair of interior grooves within either of which said spring is adapted to seat in its expanded condition, said spring being adapted to be compressed into the shaft-groove by the downward movement of said hammer to release the hammer and permit said hammer to strike the punching member near the bottom of said shaft.

7. In a punching tool for marking the surface of a metal sheet or metal block, a shaft, a tubular hammer slidable on the outside of said shaft, a spring on said shaft adapted to detachably hold said hammer from downward movement, said spring being adapted to release said hammer when said hammer has been forced downwardly to a predetermined point on said shaft, and a pointed punch member adapted to be engaged by said hammer at the bottom of said shaft.

8. In a punching tool, a tubular shaft, a double-ended tool insert secured to the bottom of said shaft, a tubular hammer slideable on the outside of said shaft, said hammer being releasably held upon said shaft, and means for releasing said hammer.

9. In a punching instrument, a shaft, a

work-engaging member detachably secured thereon, a tubular hammer on the outside of said shaft normally locked near the top of said shaft, said hammer being unlocked 5 upon the application of downward pressure thereto, whereby it will be permitted to slide down said shaft and strike said work-engaging member.

10. In a metal-punching instrument, a body, a work-engaging tool mounted on said body, said body having an annular groove near the top thereof, a split wire ring seated in said groove, the ends of said ring being normally spaced apart, a hammer on 15 said body having an interior groove within which said ring is normally adapted to expand, said ring being compressible upon the downward movement of said hammer on said body, to release said hammer and permit it 20 to slide down on the body and strike a blow on the work-engaging member under the force of gravity and the hand of the user.

11. In a punching tool, a shaft having a work-engaging member on one end thereof, 25 said shaft having an annular groove, a spring seated in said groove, a hammer having a groove initially in alinement with the groove on the shaft, said spring being initially expanded to seat within said hammer- 30 groove and also to partly fill said shaft-groove to initially prevent the hammer from sliding down the shaft, said spring being contractible upon the application of down-

ward pressure to the hammer, whereby it will be caused to completely leave the hammer-groove and permit the hammer to drop under the influence of the hand of the user and its own weight, to suddenly engage the work.

12. In a punching tool, a pointed shaft 40 having a stop near its bottom end, a tubular hammer adapted to slide upon said shaft, said hammer being initially locked on said shaft, a spring carried on said shaft, said hammer comprising a cylindrical tube having a pair of annular grooves on its inner surface, said grooves being adapted to be interchangeably engaged by said spring, one of said grooves being of greater diameter than the other, whereby the hammer may be 45 reversed for varying the tension of the spring required to release said hammer, said spring being released by the application of downward pressure to said hammer whereby the hammer will suddenly slide down the 50 shaft and engage said stop.

13. In a punching instrument, a central shaft, said shaft having a work-engaging section at one end thereof, a tubular hammer 60 slideable on said shaft for engaging said work-engaging section, and means for detachably holding said hammer at the other end of said shaft.

In testimony whereof, I have affixed my signature to this specification.

FREDERICK C. YATES.
